UNITED STATES PATENT OFFICE

ALBERT W. BRADBURY, OF CLIFTONDALE, MASSACHUSETTS, ASSIGNOR TO UNITED SHOE MACHINERY CORPORATION, OF PATERSON, NEW JERSEY, A CORPORATION OF NEW JERSEY

SHOE AND METHOD OF MAKING THE SAME

Application filed December 24, 1929. Serial No. 416,228.

This invention relates to shoes and to methods of making them, and particularly to methods of making shoes in which the welt and upper are attached together before the upper is lasted, and to shoes so made which are known in the art as "prewelt" shoes.

A usual practice in the manufacture of prewelt shoes has been, first, to sew together the margin of the upper and a welt strip, and then to assemble the upper upon a last having an insole thereon. Cement was usually applied to the lining, to the inner face of the upper or to the insole, or both, and the margin of the upper with the welt, at the sides of the shoe from tip line to breast line was worked over the insole bottom and secured in lasted position, while the cement was setting, by lasting tacks which are left upstanding so that they can be readily withdrawn. Sometimes the cement was omitted and the drying out of the tempered upper upon the last was relied upon to cause the upper to retain the shape of the last. The toe portion was usually lasted on a bed machine or by means of a wire loop and held in lasted position by a toe binding wire. The heel-seat portion of the upper, whether provided with a welt or not, was usually lasted in and secured by permanent tacks to the insole. After the cement had set and the upper had taken the shape of the last, the temporary tacks and the binding wire were removed and an outsole applied and attached to the welt, a filler having previously been placed between the insole and outsole.

In such shoes the insole, forward of the breast line, was either entirely unsecured to the upper or was held thereto only by cement, which could not be relied upon under all conditions to secure the insole in place throughout the wear of the shoe, and the use of cement in lasting occasioned considerable trouble and expense.

Objects of this invention are to provide a method by which the upper and insole of a prewelt shoe will be adequately and permanently secured together at the sides at least of the shoe and by which the use of cement may be dispensed with while the inner face of the insole is maintained smooth and intact,

and to provide a prewelt shoe having these desirable characteristics.

Accordingly the present invention consists in assembling upon a last, having an unlined insole thereon, an upper having a welt attached thereto, lasting the upper over the bottom of the insole, and securing the upper permanently in lasted position by fastenings which extend through the upper or welt, or both, and only part way through the insole, the illustrated fastenings being curved in the body of the insole with their ends directed toward the outer face of the insole, for example, by staples which extend through the welt and upper and are curved in the body of the insole toward its outer face without penetrating its inner surface. The unlined insole employed is preferably simply died out or rounded to the shape of the last bottom and thus has all of its surfaces intact and its inner and outer faces substantially smooth, flat and parallel. As illustrated, the sides of the shoe only are lasted in this manner, it being generally preferable to last the ends of the shoe by other means. It is to be understood, however, that the present invention is not limited to use at the sides of the shoe.

In another aspect the invention comprises a shoe of the prewelt type in which the upper materials at the sides of the shoe are permanently secured to an unlined insole by metallic fastenings which do not penetrate the inner face of the insole.

In the drawing,

Fig. 1 is a side elevation of apparatus for practising the invention;

Fig. 2 is a view, partly in section, illustrating the working of the upper and welt into lasted position and the insertion of a curved staple that does not penetrate the inner face of the insole; and

Fig. 3 is a perspective view of a shoe after the present method has been practised in lasting the sides.

In the practice of my improved method of making prewelt shoes in which the welt, upper and an unlined insole are secured together by metallic fastenings which do not penetrate the inner face of the insole, an upper 10 is prepared in the usual manner and a

welt 12 attached thereto, preferably by a seam 14 sewed through the welt and upper. As illustrated, the welt is laid flush with the edge of the upper, and the seam 14 extends through 5 the welt and upper near the inner edge of the welt. It is to be understood as within the invention, however, to allow either the welt or upper to extend inwardly beyond the other so that either the welt or the upper only may 10 be stapled to the insole. The lining may extend beyond the upper also for the same purpose. The upper 10 with its attached welt 12 is assembled upon a last 16 to which is secured an intact, unlined insole 18. By 15 means of a member 20 adapted to engage the shoe in the welt crease the upper and welt are worked over the insole 18 by pressure of the shoe against the member 20. Then a staple 20 is inserted through the welt and upper and into the body of the insole 18 in such a manner that the legs of the staple curve inwardly and are anchored in the body of the insole without penetrating its inner face. As 25 illustrated, the amount that the welt and upper can be worked over the shoe bottom by pressure against the member 20 is limited by a shoe edge engaging member 24 and to assist in positioning the shoe a shoe bottom rest 26 is provided. The lasting of the upper is 30 thus carried on along each side of the shoe, as illustrated in Fig. 3. Although it is within the invention to employ staples in this manner for securing the upper in lasted position at the toe and heel portions if desired, it is 35 usual and generally preferable to employ end embracing wipers or a wire loop for lasting in the toe portions of the upper and to secure the upper by tacks. The heel portion may be lasted in any usual manner whether or not 40 the welt extends around the periphery of the heel-seat and may be secured by permanent tacks.

For inserting the staples it is preferable to employ a machine of the type disclosed in 45 Letters Patent of the United States No. 1,815,295, granted July 21, 1931, in the name of George Goddu, to which reference may be had for a complete disclosure of the machine. It is sufficient, for the purpose of this 50 invention, to explain that the machine forms a staple 28 of fine wire about an inside former 30 (Fig. 2) in a plane above that in which a driver 32 acts. The formed staple is transferred by a staple transferring device 34 into 55 the plane of the driver 32 and in front of the driver. The driver is then operated to drive the staple. During the driving operation the legs of the staple engage deflectors 36 which cause the ends of the staple legs to enter the 60 upper materials in a direction nearly perpendicular to the plane of the welt and overlasted portion of the upper but curved slightly inwardly. As the driving operation continues and the legs of the staple enter 65 the body of the insole, they curve inwardly

until they reach a point preferably short of penetration of the inner face of the insole and then curve upwardly and outwardly of the shoe toward the outer face of the insole through which they entered. The legs of 70 the staple 28 are thus anchored in the body of the unlined insole 18 without penetrating its inner face and are so formed and located that the pull of the lasted upper tends to move them further in the direction in which they were driven, that is, to turn them about the axis of curvature of their legs in the same direction in which their legs were deflected or curved in the driving operation. Thus 75 the staples maintain firm hold on the upper and welt by the security of their anchorage in the insole.

After the lasting of the ends of the shoe in any suitable manner, a filler 40 is inserted and an outsole attached to the welt, usually by 80 stitches. If desired, the filler 40 may, as indicated in Fig. 2, form an integral part of the insole or it may be attached to the insole prior to or after the lasting operation.

Having thus described my invention, what 90 I claim as new and desire to secure by Letters Patent of the United States is:

1. That improvement in the methods of making shoes which consists in providing a 95 welted upper comprising an upper to which a welt has been attached, assembling the welted upper and an unlined, unchanneled insole upon a last, exerting a force applied 100 in the crease between the welt and the upper to work the welted upper over the sides of the insole, fastening the side portions of the 105 welted upper to the side portions of the insole by fastening means clenched in the interior of the insole without penetrating the inner 110 face thereof, thus leaving the toe portion and the heel-seat portion of the upper unlasted, and subsequently lasting the toe and heel-seat 115 portions and completing the manufacture of the shoe.

2. A shoe having a welted upper comprising 110 a welt and an upper secured together by a seam, an unlined, unchanneled insole, and staples extending through the welted upper but not through the insole along the opposite 115 sides of the shoe, the staples being clenched in the body of the insole without penetrating the inner face thereof, the lasted-over toe portion and heel-seat portion of the welted upper being free from staples.

In testimony whereof I have signed my 120 name to this specification.

ALBERT W. BRADBURY.
